HOT DOG VENDING BOOTH

Vincent J. Panetta, 227 E. 67th St., New York, N.Y.

Filed Feb. 21, 1966, Ser. No. 1,134

Term of patent 14 years

(Cl. D13—1)

FIG. 1

FIG. 2

FIG.3

FIG.4

FIG.5

FIG. 1 is a three-quartered perspective view of my hot dog vending booth showing my new design;

FIG. 2 is a front elevational view of my hot dog vending booth;

FIG. 3 is a top plan view of my hot dog vending booth;

FIG. 4 is a right side elevational view of my hot dog vending booth; and

FIG. 5 is a left side elevational view of my hot dog vending booth.

The dominant features of the design reside in the portions shown in full lines.

I claim:

The ornamental design for a hot dog vending booth, substantially as shown, and described.
